[57] **CLAIM**

The ornamental design of a nuptial cross, as shown.

DESCRIPTION

FIG. 1 is a left side elevational view of a first embodiment of the nuptial cross showing my new design;

FIG. 2 is a rear elevational view thereof;

FIG. 3 is a right side elevational view thereof;

FIG. 4 is a front elevational view thereof;

FIG. 5 is a top plan view thereof;

FIG. 6 is a bottom plan view thereof;

FIG. 7 is a front perspective view thereof on a reduced scale;

FIG. 8 is a left side elevational view of a second embodiment of the nuptial cross showing my new design;

FIG. 9 is a rear elevational view thereof;

FIG. 10 is a right side elevational view thereof;

FIG. 11 is a front elevational view thereof;

FIG. 12 is a top plan view thereof;

FIG. 13 is a bottom plan view thereof; and,

FIG. 14 is a front perspective view thereof on a reduced scale.
